Kogyo Kabushiki Kaisha, Nagoya-shi, Japan

Filed Oct. 23, 1970, Ser. No. 25,619

Claims priority, application Japan Apr. 24, 1970

Term of patent 14 years

Int. Cl. D18—01

U.S. Cl. D64—11

FIG. 1 is a perspective view of a typewriter casing showing our new design, with the line space lever in its folded, inoperative position and with the carrying bar drawn out to its operative position;

FIG. 2 is a left side elevational view thereof with the carrying bar in withdrawn position and the line spacing lever in raised position;

FIG. 3 is a rear elevational view thereof; and

FIG. 4 is a front elevational view thereof, with the carrying bar withdrawn to its inoperative position.

We claim:

The ornamental design for a typewriter casing, as shown.
